ABSTRACT: A frequency-sensitive circuit has first and second input terminals and first and second output terminals with the second input and output terminals interconnected. Between the input terminals is connected a phase-shifting network, and a transistor has its base connected to the phase-shifting network, its emitter connected to one of the input terminals and its collector connected to the other input terminal through an impedance. The output from the circuit changes polarity at a predetermined frequency.

BRAKING SYSTEMS FOR VEHICLES

This invention relates to frequency-sensitive circuits particularly, but not exclusively, for use in rail vehicles.

A circuit according to the invention comprises in combination first and second input terminals for connection to an AC supply of varying frequency, first and second output terminals, the second input and second output terminals being interconnected, a phase-shifting network connected between the first and second input terminals, and a transistor having its base connected to the phase-shifting network, its emitter connected to one of the input terminals and its collector connected to the other input terminal through an impedance, the first output terminal being connected in the circuit in a position such that the output at the output terminals changes polarity at a predetermined frequency.

The accompanying drawing is a circuit diagram illustrating one example of the invention.

The drawing illustrates the application of the invention to the control of the braking of a rail vehicle. The wheel to be controlled drives an alternator 10 driven from the wheel axle, and the alternator produces an alternating current signal between a pair of supply lines 11, 12. Connected in series between the lines 11, 12 are resistors R1 and R2 and a capacitor C1, the junction of the resistors R1, R2 being connected to the emitter of a PNP transistor Q1, the base of which is connected to the junction of the resistor R2 and capacitor C1. The collector of the transistor Q1 is connected to the line 12 through a capacitor C2, and is further connected to the line 12 through a resistor R3 and a capacitor C3 in series, the junction of the resistor R3 and capacitor C3 being connected to the base of an NPN transistor Q2 through a resistor R4. The transistor Q2 has its emitter connected to the line 12 through a diode D1 and resistor R5 in series, and its collector connected through a diode D2 to the junction of a pair of resistors R6 and R7 connected in series between the lines 11, 12. The emitter of the transistor Q2 is further connected to the gate of a thyristor T1, the cathode of which is connected to the line 12, and the anode of which is connected through a relay coil to the cathode of a further thyristor T2, the anode of which is connected to the line 11 through a resistor R9. The gate of the thyristor T2 is connected to the junction of a resistor R8 and capacitor C5 connected in series between the lines 11, 12, and the coil 13 is bridged by a capacitor C4. The relay is conveniently a Reed relay having normally open contacts 13a which are protected by a metrosil W1. When the contacts of the relay are closed, they serve to energize a brake control 14 comprising a solenoid driven by a DC supply, the solenoid controlling a valve which when the relay contacts 13a are closed reduces the braking pressure which can be applied to the wheel.

The transistor Q1 receives its base signal from the junction of the resistor R2 and capacitor C1, and so that the base signal will be phase shifted with respect to the signal between the lines 11, 12 by an amount dependent on the frequency of the alternator, which is of course dependent on the speed of the wheel. Depending on the frequency, the transistor Q1 will conduct either during the positive half cycles of the supply between the lines 11, 12 or during the negative half cycles, and the arrangement is such that as the speed of the wheel increases from zero, the capacitor C2 will acquire a negative charge during each cycle, this negative charge increasing with wheel speed until a predetermined value is reached, and then starting to decrease again. As wheel speed increases further, the negative charge continues to decrease, until at some predetermined wheel speed determined by the parameters of the circuit, the charge acquired by the capacitor C2 becomes positive, and then continues to become increasingly positive as wheel speed increases further. It will be apparent that by suitable choice of the circuit parameters, it can be arranged that at a desired predetermined speed the charge on the capacitor C2 becomes positive. When the charge on the capacitor C2 is positive, the transistor Q2 is turned on, the resistor R3 and capacitor C3 acting as a delay network so that

transient variation in the speed of the wheel, as for example, if the wheel should skid, do not effect the circuit. When the transistor Q2 conducts, it provides gate current to the thyristor T1, which, assuming for the moment that the thyristor T2 is conductive, energizes the relay to reduce the braking effort which is available. Thus, if the brakes of the vehicle are applied, then if, as will usually happen, the speed of the wheel is above the predetermined value, the charge on the capacitor C2 will be positive, and the transistor Q2 will turn on, so that the thyristor T1 conducts and the relay is energized so that only the reduced braking effort is available. As the wheel speed falls, a point is reached at which the charge on the capacitor C2 ceases to be positive, so that the transistor Q2 no longer conducts, no gate current is supplied to the thyristor T1, and the relay is deenergized, so that the full braking effort is applied. The transistor Q1 operates in the switching mode. The resistor R4 reduces the discharge rate of the capacitor C3 during the negative half cycles, and the diode D1 compensates for changes in the gating characteristics of the thyristor T1 with temperature. The charge which is stored in the capacitors C2 and C3 ensures that if the relay is energized and the wheel slips, the relay will remain energized for about two seconds, by which time the wheel will probably have ceased to slip, bearing in mind that the unit shown is intended to be used in conjunction with a separate unit for preventing or minimizing wheel slip.

When the thyristor T1 is turned on to energize the relay, the current must of course flow through the thyristor T2, the bias for which is taken from the junction of a resistor R8 and capacitor C5. The purpose of this arrangement is to control the mean current which flows through the relay. As the wheel speed increases, the mean current would, in the absence of the thyristor T2, increase, with possible damage to the relay. However, by virtue of the phase shift produced by the resistors R8 and capacitor C5, the point in each positive half cycle at which the thyristor T2 becomes conductive is delayed with increasing voltage between the lines 11, 12, so that the mean current flow in the relay remains within acceptable limits as the speed of the wheel increases.

The primary use of the system described is to enable the braking effort of a high-speed train to be increased when the speed falls below a set value, typically 100 m.p.h., so enabling best use to be made of the adhesion, which increases with decreasing speed. The arrangement is particularly useful where an antiskid unit is employed, because the low adhesion at high speeds can cause excessive operation of the antiskid unit. The system can also be used with advantage in trains having some stock with disc brakes and some with block brakes. A difficulty with such mixed stock is that the torque of the disc brakes is substantially constant, whereas the torque of the block brakes increases substantially at low speeds. The system described can be used to minimize this disadvantage by arranging that, in the case of the disc brakes only, the braking effort is increased below a set speed, typically 30 m.p.h.

The transistor Q1 could be replaced by an NPN transistor, or a field effect transistor having its gate, source and drain connected in the same way as the base, emitter and collector at the transistor Q1. It is to be understood that references in the claims to the base, emitter and collector of a transistor include the equivalent electrodes, namely gate, source and drain, of a field effect transistor.

Having thus described my invention what I claim as new and desire to secure by Letters Patent is:

1. A frequency-sensitive circuit comprising in combination first and second input terminals for connection to an AC supply of varying frequency, first and second output terminals, the second input and second output terminals being interconnected, a resistance chain and a first capacitor connected in series between the first and second input terminals, and a transistor having its base connected to the junction of the resistance chain and first capacitor, its emitter connected to the first input terminal through part of the resistance chain, and its collector connected to the first output terminal, said collector

being further connected through a second capacitor to said second input terminal, whereby the output at the output terminals changes polarity at a predetermined frequency.

2. A circuit as claimed in claim 1 including a switching stage powered by the AC supply and operable above the predeter-

mined frequency, and a delay network coupling the output terminals to the switching stage to prevent operation of the switching stage by transient increases in frequency above the predetermined level.
